Primary Examiner—James R. Largen

[57] CLAIM

The ornamental design for a speedometer cable grease fitting, as shown and described.

DESCRIPTION

FIG. 1 is a perspective view of a speedometer cable grease fitting showing my new design;

FIG. 2 is a side elevational view thereof, the other sides being the same as the side shown;

FIG. 3 is the top view thereof; and,

FIG. 4 is the bottom view thereof.
